UNITED STATES PATENT OFFICE.

WILLIAM J. SHERIFF, OF PITTSBURG, PENNSYLVANIA.

DOUBLE-HEADED EJECTOR.

SPECIFICATION forming part of Letters Patent No. 277,072, dated May 8, 1883.

Application filed February 15, 1883. (Model.)

To all whom it may concern:

Be it known that I, WILLIAM J. SHERIFF, of Pittsburg, in the county of Allegheny and State of Pennsylvania, a citizen of the United States, have invented certain new and useful Improvements in the Construction of Double-Headed Ejectors; and I do hereby declare the following to be a full, clear, and exact description of the same, reference being had to the accompanying drawings, in which—

Figure 1 is a longitudinal section of an ejector embodying my invention. Fig. 2 is a detached view of the steam-jet, showing its construction. Fig. 3 is an end view of the steam-jet.

Like letters refer to like parts wherever they occur.

My invention relates to certain new and useful improvements in double-headed steam-ejectors, and has for its object to reduce the cost of manufacture, and facilitate the fitting and finishing of the devices.

I will now proceed to describe my invention more specifically, so that others skilled in the art to which it appertains may apply the same.

The head A B, I form in two parts. The part A, or base, has the induction-orifice a^2 , screw-threaded for the reception of the suction-pipe, and is provided with a screw-thread, a^3 , for the reception of the body or combining-section B of the ejector. This section A, I preferably form by casting, and provide it with a curved steam-induction pipe, E, which is enclosed by and centered with the head, and threaded for a nozzle, D.

D indicates a steam-nozzle. This nozzle is formed with a threaded shank, a^4 , which engages with the screw-thread a^3 , and a threaded slotted shoulder or flange, a^5 , for the reception of the inner head, C.

d^2 indicates the slots in the shoulder or flange of nozzle D to permit the passage of the water, so that the ejector may take its water not only around but through the inner head, C.

C indicates the inner head, which is coniform, and threaded at its base to screw upon the shoulder a^5 of the jet.

B indicates the combining-section of the ejector-head, which is bell-shaped at the point b , and threaded at one end, as at b' , to engage

with the base-section A, and at the other end to receive the discharge-pipe e^2 .

The several parts before recited constitute the ejector, and, being united as shown in Fig. 1, will operate as follows: The steam, being admitted by the curved induction-pipe E to the head, will in escaping by jet D form a vacuum in the head A and induce the flow of water. The head having filled, a limited stream will first pass to the inner head, C, as indicated by the arrows 1, which stream, having in a measure condensed the steam and received its velocity, will induce a current through the side channels around the head, as indicated by the arrows 2, and the whole volume of fluid will then be discharged through the discharge-pipe e^2 .

The advantages of an ejector constructed as herein described are that the double-headed ejector, being in two sections, can be finished by the use of inexpensive tools. Any defects in the castings can be at once detected. The inner head and combining-section, which are parts liable to wear, can be readily replaced, and from the high finish thus attainable I have found that I can save twenty per cent. in steam-pressure, and obtain ten per cent. in the volume of water elevated and discharged, over other styles of double-head ejectors.

I am aware that double-headed ejectors have heretofore been constructed in two sections, and also that a curved centrally-arranged steam pipe or jet has been cast integrally with a non-divisible ejector-head, and do not herein claim either separately, for the reason that in the one case the increased number of parts add to the cost of manufacture and demand special skill and care in finishing and fitting up, and in the other—viz., the non-divisible head—it is only with great difficulty that the interior can be properly finished, while by the construction herein shown and described the separate parts are reduced in number, and at the same time the whole interior of the ejector is accessible for finishing and repairing the same.

Having thus described my invention, what I claim, and desire to secure by Letters Patent, is—

1. In a double-headed ejector, the combination of the centrally-separable sections A B, 100

the section A having the centrally-arranged curved steam-pipe, and the induction-port a^2 , aligned with the eduction-port of the section B, substantially as and for the purpose specified.

- 5 2. In an ejector, the combination of the base-section A, having the central induction-port, a^2 , the curved centrally-arranged steam-induction pipe E, the flanged nozzle D, its flange 10 provided with water-passages, the inner head, C, supported by the flanged nozzle, and the

detachable combining-section B, having its eduction-port aligned with the induction-port a^2 of the base-section A, substantially as and for the purpose specified.

15

In testimony whereof I affix my signature, in presence of two witnesses, this 7th day of February, 1883.

WILLIAM J. SHERIFF.
